UNITED STATES PATENT OFFICE

108,110

DESIGN FOR A BARBER'S CABINET OR SIMILAR ARTICLE

Ross H. Trickle, Newark, Ohio

Application April 7, 1936, Serial No. 61,996

Term of patent 3½ years

To all whom it may concern:

Be it known that I, Ross H. Trickle, a citizen of the United States, residing at Newark, in the county of Licking and State of Ohio, have invented a new, original, and ornamental Design for a Barber's Cabinet or Similar Article, of which the following is a specification, reference being had to the accompanying drawing, forming part thereof.

The figure is a perspective view of a barber's cabinet or similar article showing my new design.

I claim:—

The ornamental design for a barber's cabinet or similar article as shown.

ROSS H. TRICKLE.
